(57) CLAIM

The ornamental design for a cosmetics case, as shown and described.

DESCRIPTION

FIG. 1 illustrates the case with the cover open and with the cosmetic pans in place;

FIG. 2 illustrates the case with the cover open, and with the cosmetic pans removed to disclose the underlying surfaces;
FIG. 3 illustrates the case with the cosmetic pans in place and with the upper tray partially tilted;

FIG. 4 illustrates the case with the upper tray tilted to a substantially vertical position providing access to the lower compartment;

FIG. 5 illustrates the case with the cover closed; and,
FIG. 6 is an exploded view of the case illustrating the individual components.
